UNITED STATES PATENT OFFICE.

ERNST OLDENBUSCH, OF NEW YORK, N. Y., ASSIGNOR TO WILLIAM SCHIMPER & CO., OF SAME PLACE.

SNAP-LOCK FOR POCKET-BOOKS.

SPECIFICATION forming part of Letters Patent No. 427,790, dated May 13, 1890.

Application filed December 31, 1889. Serial No. 335,477. (No model.)

To all whom it may concern:

Be it known that I, ERNST OLDENBUSCH, of the city and county of New York, in the State of New York, have invented a certain 5 new and useful Improvement in Snap-Locks for Pocket-Books, of which the following is a specification.

My improvement relates to snap-locks for locking the flaps of pocket-books to the main 10 or body portion thereof.

I will describe my improvement in detail, and then point out the novel features in the claim.

In the accompanying drawings, Figure 1 is 15 a vertical section of a lock for a pocket-book embodying my improvement. Fig. 2 is a plan or top view of a blank previous to being stamped up. Fig. 3 is a view looking from the under side of the said blank after the 20 same has been stamped up. Fig. 4 is an edge view of a blank after the same has been stamped up, the same being shown as inverted. Fig. 5 is a view in perspective of a portion of a purse with the lock attached.

25 Similar letters of reference designate corresponding parts in all the figures.

In carrying out my improvement I take a piece of metal and stamp or otherwise cut from it a blank A, which blank comprises a 30 substantially circular main portion a, from which extend prongs a', of which I have shown three. Upon one side of the main or body portion A are formed projections a², and intermediate of the projections a² a tongue a³. In the projections a² are formed holes a⁴, and in the main or body portion a is formed a hole a⁵. The blank, having been thus cut, is subjected to the action of dies and is stamped up into the form shown more clearly 35 in Figs. 1, 3, and 4.

About the edge of the main or body portion a there is formed a flange b, from which the prongs a' project at approximate right angles to the plane of the main or body portion a.

40 Adjacent to the projections a² there is formed upon the upper side of the blank a rib or projection b'. The projections a² are so bent as to extend outwardly from the back and into planes at approximate right angles to the

plane of the main or body portion a. The 50 holes a⁴ in the projections a² will then be opposite each other. The rib or projection b' is at the rear of the projections a². Between the projections a² the tongue a³ is bent downwardly in the same direction as are the 55 prongs a'.

D designates a pin, which is passed through the hole a⁵ in the blank A after the blank has been stamped up, and also through a suitable aperture formed near one end of a flat 60 spring d. The pin D is upset outside the spring d, thus securing the spring to the blank A.

F designates a snap-plate, by which a flap is secured at its free end to the main or body 65 portion of a pocket-book. This snap-plate comprises a portion f, which portion is substantially circular, or, in other words, conforms in shape to the main or body portion a of the blank A. Upon one of its edges it is provided with an inwardly-bent tongue or projection f', which inwardly-bent projection forms near its extremity a cam f². At the sides of the projections f' are lugs f³, which lugs are adapted to be passed through the 70 holes a⁴ in the projections a². Said projections are then squeezed toward each other, and the snap-plate thus becomes journaled upon the projections a², and may be swung freely to and fro thereon. The cam f² bears 75 upon the spring d. When the snap-plate F is raised or lowered, the cam will deflect the spring d, and should the snap-plate be shut down upon the pin D, as it will be in order to secure the flap, the spring will hold it in such 80 closed condition. When the snap-plate has been sprung into the other position, or that illustrated in Fig. 1, in order to release the flap the cam f² will strike against the inwardly-bent tongue a³, which latter then acts 85 as a stop to prevent a too extended movement of the snap-plate in this direction.

It will be seen that by my improvement a ready means is afforded for preventing the snap-plate from being opened too far.

90 It is to be understood that the blank A is secured to the pocket-book by means of the prongs a'.

What I claim as my invention, and desire to secure by Letters Patent, is—

The combination, with a blank adapted to be secured to a pocket-book and provided with a flanged portion terminating in ears and with a bent tongue located between the ears, of a snap-plate mounted in the said ears and provided with a cam, and a spring lo-

cated in position to engage the cam, the bent tongue forming a stop for the snap-plate, substantially as herein described. 10

ERNST OLDENBUSCH.
